DISPENSING CLOSURE CAP

Robert Hollister, Larchmont, N.Y., assignor to American
Can Company, New York, N.Y., a corporation of New Jersey

Filed July 29, 1958, Ser. No. 51,982

Term of patent 14 years

(Cl. D58—26)

FIG. 1

FIG. 2

Fig. 1 is a perspective view of a dispensing closure cap, showing my new design; and

Fig. 2 is a sectional view thereof taken through the center of one half of the cap in Fig. 1.

The side not shown is the same as the side shown.

I claim:

The ornamental design for a dispensing closure cap, substantially as shown and described.
